UNITED STATES PATENT OFFICE.

ALFRED WEILAND, OF PHILADELPHIA, PENNSYLVANIA.

CARBURETER FOR INTERNAL-COMBUSTION ENGINES.

1,345,297.

Specification of Letters Patent. Patented June 29, 1920.

Original application filed February 17, 1917, Serial No. 149,185. Divided and this application filed November 30, 1917. Serial No. 204,547.

To all whom it may concern:

Be it known that I, ALFRED WEILAND, a citizen of the United States, residing at Philadelphia, in the county of Philadelphia and State of Pennsylvania, have invented a certain new and useful Carbureter for Internal-Combustion Engines, of which the following is a specification.

The present application is filed as a division of my co-pending application Serial No. 149,185 and the invention herein relates generally to the control regulation and feeding of liquid fuel to explosive engines and relates more particularly to the supply and discharge of such fuel to the carbureting chamber and the motor intake.

It is an object of the invention to provide means to regulate and proportion the supply of fuel according to speed and load conditions whereby for maximum load and low speed conditions, a mixture rich in fuel is maintained to meet the existing condition, and for minimum low and high speed a correspondingly starved or weak fuel mixture is maintained while for all conditions of load and speed, there will be an effective regulation of the fuel to meet the particular existing condition. It is a further object to provide a fuel regulating means which acts promptly upon change of load or speed conditions eliminating a period of lag and preventing a flooding of the carbureting chamber when a minimum supply of fuel is required or leaving it relatively empty when a maximum supply is required.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings:

Figure 1 represents a plan of a carbureter embodying my invention.

Fig. 2 represents a section on line 2—2 of Fig. 1.

Fig. 3 represents a section on line 3—3 of Fig. 1 on a larger scale.

Fig. 4 represents a section on line 4—4 of Fig. 1 on a larger scale.

Fig. 5 represents a sectional elevation of another form of the invention.

Fig. 6 represents a plan of the same.

Fig. 7 represents an end elevation, a portion being broken away to show one of the fuel nozzles in section.

Fig. 8 represents a section on line 8—8 of Fig. 5.

1 designates the casing of the carbureter 65 which forms a main liquid fuel reservoir 2 and a carbureting chamber 3, the latter being open through the intake 4 to the air at one end and communicating with the motor intake passage 5 at the opposite end. The 70 throttle valve 6 is pivoted for swinging movement across the chamber 3 and is under the control of the throttle lever 7 as will be understood. The main fuel reservoir 2 has direct communication with the main jet 75 or nozzle 8 which is located in the carbureting chamber between the air intake and throttle, and has its outlet at substantially the normal liquid level of the main reservoir so that there is a supply of liquid 80 fuel ready to be drawn out and mixed with the air to form the explosive mixture.

Since the carbureter of the present invention is adaptable for use with many types of fuel feed systems and fuel replenishing 85 means, the present description will be confined to the carbureter structure specifically with a brief general outline of the fuel feeding means. Thus in Figs. 1 and 2, a fuel feeding means for the main reservoir 2 is 90 illustrated embodying two supply chambers 9 and 10, the action of which is alternate, that is one is an active feeding medium while the other is replenishing its fuel supply from a suitable source, while in Figs. 95 5 to 7 inclusive a single main reservoir 2 is provided for delivering fuel to the jets.

12 designates the main fuel inlet conduit for furnishing liquid fuel to the supply chamber or chambers, as the case may be, 100

and in the latter it is subdivided into channels 13 leading to the respective chambers 9 and 10.

Referring now to the auxiliary jet construction, it will be seen that the casing 1 forms a supplemental fuel reservoir 14 located preferably adjacent the position of the throttle valve and in communication with the main fuel reservoir 2 by way of the passage 15. In the construction shown in Fig. 3, 16 designates a suitable bushing fixed to the casing 1 extending within the reservoir chamber 14 and having a bore 17 therein which is suitably enlarged to receive the fuel nozzle or jet 18. The discharge end of the jet 18 is preferably slightly below the normal fuel level in the main reservoir 2 so that when the carburetor is not in operation the fuel will overflow and form a priming puddle in the auxiliary reservoir 14. The bushing 16 is further exteriorly of reduced diameter for a portion of its length to form a channel 19 by which the air entering through the port 20 may reach the open end of the bushing 17 and thus mix with the fuel drawn out of the jet 18. The bore 17, communicates with a conduit 21 which passes through the casing wall and has its discharge end between the throttle and the motor intake so that the mixed air and fuel from this auxiliary jet is drawn directly to the motor intake whether the throttle valve is open or closed.

The throttle valve 6 in the present instance is connected to the oscillative sleeve 22, while the latter is pinned as shown at 23, or by equivalent means to the spindle 24 which carries the throttle lever 7. 25 designates a sleeve having screw-threaded connection with the casing 1 and bored out to form a second auxiliary fuel reservoir 26, the said bore having a reduced opening 27 extending through the part 25 and communicating with the passage 15 leading to the main fuel reservoir 2, so that the fuel may flow freely to the reservoir 26 to the normal level. In the present instance, the spindle 24 is provided with a passage 28, the inner end of which terminates below the normal liquid level, while the outer end has free communication with the atmosphere, so that air drawn through this passage bubbles through the liquid fuel and the resulting mixture is then drawn into the carbureting chamber 3 by way of the port 29 formed in a laterally disposed boss 30 of the throttle valve 6. By reference to Fig. 1, it will be seen that the port 29 discharges the mixture on the carburetor side of the throttle and is consequently idle in closed position of the throttle valve. As the throttle opens, however, this jet comes into operation and discharges its mixture into the carbureting chamber at a point or points removed from the bound-

ing wall of said chamber. This action is quite important as the fuel particles are carried away from the wall and have no opportunity to adhere thereto. Such adhesion considerably lessens the mixture value.

The inner end of the hollow spindle 24 is of reduced diameter to form a circumferential space 31 as a part of the auxiliary reservoir 26, the said space communicating with the annulus 32 with which the port 29 communicates.

In Figs. 5 to 7 inclusive, the auxiliary jet, formed in the wall of the casing and having its mixture outlet arranged to discharge on the motor intake side of the throttle valve 6, is slightly modified in construction by providing a tubular member 33 having threaded engagement with the casing and terminating in close proximity to the bottom of the reservoir chamber 14. It is of open ended construction, thereby providing an air channel 34 which delivers air below the normal liquid level, so that the air bubbling through the liquid fuel becomes saturated and discharges through the port 21. This is merely an equivalent for the jet structure shown in Fig. 3. Having now fully described the fuel jet structure of the carburetor embodying the present invention, brief reference will be made to the fuel feeding mechanism. In Figs. 1 and 2 the fuel feed embodies a vacuum means for replenishing the supply of chambers 9 and 10, the same being operative through ports 34 leading from the motor intake to the respective chambers 9 and 10. 35 designates flap valves respectively controlling the fuel inlets for fuel from the low level source. These valves 35 are loosely held respectively at one end by suitable fastening means and normally seat over the outlet channels 13. The pressure of the incoming fuel is sufficient to lift these valves so that it has free flow into the respective reservoirs.

Each chamber contains a float 36 arranged to operate and control the respective valves 37 for the outlets to the main reservoir 2 and these valves are suitably controlled by a pivoted lever 38 in such a manner that only one valve 37 may be open at a time. Suitable air vents 39 are provided for the main reservoir 2 as shown in Fig. 2. In the construction of Fig. 5, the fuel jets are supplied from the main reservoir 2 which in turn is filled by way of the inlet 12, this latter being controlled by a float 40 and valve 41 as will readily be understood.

The operation of the carburetor is as follows: Under rest conditions, the fuel is substantially at the same level in the auxiliary reservoirs 14 and 26, the main reservoir 2 and the main fuel jet 8 and with the throttle closed any drop in pressure in the motor intake due to turning over the motor will not

affect either the main jet 8 or the auxiliary jet 29. This does, however, leave what I term the slow speed and starting jet free to supply mixture to the motor since the port 21 opens on the motor intake side of the throttle valve. This priming mixture is therefore always available under starting conditions and insures a mixture rich in fuel to meet the required condition.

10 As soon as the motor has come up to speed, the throttle is opened to bring into operation the main mixture supply from jet 8 or at least to render the second auxiliary jet operative. It is evident that a prolonged operation of the motor will cause the auxiliary reservoir 14 to be depleted of its initial puddle of fuel and consequently the jet mixture is so starved or cut down as to be ineffective to meet the varying demands 15 of normal operation of the motor. A partial opening of the throttle relieves this condition, since it immediately renders the second or intermediate speed jet operative and this in turn is augmented by a mixture 20 of air and fuel from the main jet 8 and air inlet 4. As the throttle opens, the intermediate jet outlet 29 travels away from the wall of the carbureting chamber, swinging 25 toward the motor intake so that its mixture mingles directly with the main mixture from 30 the jet 8, thereby supplementing it in the required manner and insuring an effective charge. When the throttle is moved toward its closed position, the main mixture is cut 35 down while the intermediate jet remains operative until cut off by the closing of the throttle and after the motor comes to rest the fuel overflows into the slow speed reservoir and leaves it ready for priming under 40 starting conditions.

The action of the intermediate jet is furthermore most essential since its outlet 29 moves through an area of the carbureting chamber where the incoming air has its 45 greatest velocity with the result that the fuel is swept from the outlet in the form of a vapor which is instantaneously diffused and mixed with the air to form an effective mixture. Thus under some conditions, the 50 air drawn in by way of passages 4 may move so slowly past the main jet as to draw off some of the liquid fuel but not sufficiently fast to vaporize and mix it with the air but at the outlet 29 the velocity is always such 55 as to cause proper vaporization and prevent an uneven mixture with the air. Naturally, the more nearly the throttle is closed, the greater is the velocity of the air and so the mixture is uniform on substantially all conditions. The puddle of liquid fuel in the 60 jet chamber 26 is considerably reduced as soon as the outlet 29 goes into operation but is not completely emptied. The reason for this is that the port 27 and passage 28 are

proportioned with respect to each other and 65 while the discharge end of the passage is often unsealed by the drop of the liquid level, the air then passing through is not sufficient to counterbalance the incoming fuel through port 27. In consequence, there 70 is always an operative quantity of liquid fuel for the auxiliary jet outlet 29 which reinforces the action of the main jet to the extent desired. The slow speed jet 18 is also proportioned with regard to its air and fuel 75 inlets and hence while its mixture may be materially starved or cut down, it does not under ordinary conditions of operation become entirely inactive as a mixture supply. It will now be apparent that I have devised a novel and useful construction which embodies the features of advantage enumerated as desirable in the statement of the invention and while I have in the present instance shown and described the preferred 80 embodiment thereof which has been found in practice to give satisfactory and reliable results, it is to be understood that the same is susceptible of modification in various particulars without departing from the spirit or 85 scope of the invention or sacrificing any of its advantages.

What I claim is:

1. In a device of the character stated, a casing providing a carbureting chamber, a main fuel reservoir and an air inlet to said chamber, a main fuel jet, a throttle valve provided with an outlet to said carbureting chamber, said outlet being cut off from the motor intake in closed position of said throttle, and open in open position of said throttle, an auxiliary fuel reservoir formed in said throttle and in communication with said outlet, and a supplemental air supply to said throttle reservoir. 105

2. In a device of the character stated, a casing providing a carbureting chamber, a main fuel reservoir and an air inlet to said chamber, a main fuel jet, a throttle valve provided with an outlet to said carbureting 110 chamber, said outlet being cut off from the motor intake in closed position of said throttle and arranged to open and move with said throttle away from the wall of the casing and toward the motor intake, an auxiliary fuel reservoir formed in said throttle and in communication with said outlet, and a supplemental air supply to said throttle reservoir. 115

3. In a carbureter, a casing providing a 120 substantially horizontal carbureting chamber communicating at opposite ends respectively with an air supply and the intake of a motor of the explosive type, a main fuel reservoir, a main fuel jet arranged in said 125 chamber adjacent the entering air supply, a second fuel jet located between said main jet and the motor intake, a throttle valve

pivoted upon said second jet and provided with a laterally disposed outlet arranged to be closed by the wall of said chamber in closed position of said throttle, and open in open position of said throttle, and a third fuel jet having uncontrolled communication with said chamber between said throttle

valve and the motor intake, all of said jets having communication with said main reservoir.

10

In testimony whereof, I have hereunto signed my name.

ALFRED WEILAND.
